UNITED STATES PATENT OFFICE.

OSCAR H. PIEPER AND ALPHONSE F. PIEPER, OF ROCHESTER, NEW YORK.

HOT-AIR SYRINGE.

1,369,935.

Specification of Letters Patent.

Patented Mar. 1, 1921.

Original application filed August 13, 1917, Serial No. 185,863. Divided and this application filed October 11, 1918. Serial No. 257,734.

To all whom it may concern:

Be it known that we, OSCAR H. PIEPER and ALPHONSE F. PIEPER, both of Rochester, in the county of Monroe and State of New York, have invented certain new and useful Improvements in Hot-Air Syringes; and we do hereby declare the following to be a full, clear, and exact description of the same, reference being had to the accompanying drawings, forming a part of this specification, and to the reference-numerals marked thereon.

The present invention relates to hot air syringes of the kind employed by dentists for cleaning and drying cavities in teeth, and is a division of our application for hot air syringes, Serial No. 185,863, filed Aug. 13, 1917.

The object of our invention is to provide an improved electric heating element for syringes of this kind which is efficient in use, and the parts whereof are readily assembled in such a manner as to obtain air-tight joints and perfect insulation. To these and other ends the invention consists in certain improvements and combinations of parts, all as will be hereinafter more fully described, the novel features being pointed out in the claims at the end of the specification.

In the drawings:

Fig. 1 is an enlarged longitudinal sectional view of a hot air syringe constructed in accordance with our invention;

Fig. 2 is an elevation looking in the direction of the arrow in Fig. 1, parts of the view being shown in section;

Fig. 3 is a horizontal sectional view on the line 3—3 of Fig. 2;

Fig. 4 is an enlarged view of the heating element removed;

Fig. 5 is a detail view of the sustaining member for attaching one end of the heating coil, and

Fig. 6 is a sectional view on the line 6—6 of Fig. 4.

Similar reference characters throughout the several views indicate similar parts.

A syringe constructed in accordance with our invention embodies a head portion 1, on which is fitted a tubular hand grip 2, and having a recess receiving the casing 4, containing the heating element 5 and carrying the nozzle 6 at its outer end. The head 1 has a portion containing the air passages which is connected to the pipe 7 leading to a

source of air under pressure and within the hand grip 2. Within the head is a valve chamber 9 containing a valve head 10, on a stem 11, having a thumb piece 12 on its outer end. The valve head is normally held against its seat by a spring 13, resting in a recess in a screw plug 14, removably closing the valve chamber.

The heating element 5 is shown in detail in Fig. 4 and consists of an outer tube 15 closed at its inner end 16, and expanded at its outer end, as at 17, to receive a correspondingly expanded end 18 on an inner tube 19 which is spaced from the outer tube to provide an air passage between them. Within the inner tube is located the heating coil C of fine elastic wire, one end of the coil being looped under the head of a screw 20, which passes through insulating washers 21, on each side of the end 16 of the outer tube, and secured by a lock nut 22. The other end of the heating element, or coil, is engaged by a hook 23 on a transversely extending portion 24 of a ring 25 which is placed within the expanded end 18 of the inner tube and held thereon by a washer 26 over which the end 17 of the outer tube is formed. The heating coil C is supported solely by means of the attaching portions at its opposite ends and in order to prevent any accidental contact of the coil with the tube 19, and consequent short circuiting of part of the coil, we provide an insulating sleeve 19^a fitting within said tube and surrounding the coil.

The heating element is located within the casing 4 and is secured therein by means of the screw 20, which co-operates with a securing member in the form of a hollow sleeve 27 permanently fastened by means of a nut 28 to an insulating partition or disk 29 set within the end 3 of the head 1. The disk 29 is prevented from removal by engagement therewith, of a flange 30 on a tube, or sleeve, 31, surrounding the heating element and spaced therefrom except at its outer end which is engaged by the expanded end 17 of the heating element to make an air tight joint. An insulating ring 32 bears on the outside of the flange 30, and is forced against it by a shouldered ring 33, which in turn is engaged by the inner end of the casing 4, and secured by means of the latter, which is itself threaded into the recess of the head 1. A sleeve 55 of asbestos, or other poor conductor of heat, is inserted between 105 110

the tube 31 and the outer casing, or sheath, 4 to prevent loss of heat by radiation from the coil C.

The air is admitted by the valve 10 from 5 the passage 8 into a passage 34 in and through a central passage 35 and transverse apertures 36 in the sleeve 27. It then passes between the tube 31 and the outer wall 15 of the heating element, until it reaches apertures 37 in the latter, which are adjacent the expanded end 17. The air then passes inwardly between the tubes 19 and 15, of the heating element, and around the end of the inner tube, in the opposite direction within 10 the tube 19, past the heating coil and through the openings in the ring 25 and the central aperture in the washer 26, escaping through the nozzle 6.

In order to enable the circuit through the 20 coil C to be closed when the air is admitted, we provide a switch arm 38 which is actuated by a plunger 40 arranged beneath the valve thumb piece 12 and is adapted to engage an insulated contact plate 41 connected by a wire 42, passing through a channel 42^a in the head 1 and through the sleeve 27 to the tube 31. The switch arm 38, which makes electrical contact through the tubes 15 and 19, to one end of the heating 25 coil C, is carried by an air supply pipe attaching sleeve 43.

The member 45 is connected by a wire 52 leading through a channel 52^a to the nut 28, the latter making electrical connection 30 through the sleeve 27 and screw 20 to the inner end of the heating coil. Electrical connection is preferably made to an electric circuit by wires A and B which lead within the air pipe 7, and are connected respectively to outer and inner contact sleeves 53 and 54, the former engaging the terminal sleeve 43, while the latter makes contact with the tubular member 45 which constitutes the other terminal of the instrument 35 circuit. When the thumb piece 12 of the valve is depressed, the current passes from conductor A through sleeves 53 and 43, switch arm 38, contact plate 41, wire 42, tube 31, heating element C, screw 20, sleeve 27, nut 28, wire 52, tubular member 45, sleeve 54, conductor B. At the same time air is admitted from the pipe 7 through the central passages in the contact sleeves 53 and 54, through member 45, passage 8, valve 40 chamber 9, and as before described past the heating coil into the nozzle 6.

It will be observed from the foregoing that the air conducting portion carrying the nozzle and the heating elements therein are 45 both so arranged that they may be assembled independently of the head and handle portion of the instrument, and secured to the latter by inserting the end of the tube 4 in the recess of the head 1, and 50 screwing it into position therein. This act

causes the compression of the collar 33 against the washer 32 bearing against the flanged end 30 of the interior sleeve 31, which in turn compresses the washer 29 and causes the sleeve mounted thereon to be 55 rigidly held in place.

We claim as our invention:

1. A heating member for hot air syringes comprising an outer tube having its outer end expanded and its inner end flanged inwardly, an inner tube suspended within the outer tube and having an outer flanged end fitting that of the outer tube, a suspension member at the outer ends of the tubes, an electric heating coil having one end attached 75 to said member and a screw attached to the other end of the coil and projecting through the inwardly flanged end of the outer tube, insulating washers on the screw embracing opposite sides of the flange of said tube and 80 a clamping nut on the screw.

2. In a syringe, a head provided with a recess, a partition across said recess, a tubular casing secured in said recess, a sleeve extending through said partition, an outer 90 tube within said casing having a closed end supported on said sleeve, said tube being open at its opposite end and provided with apertures adjacent said open end, an inner tube spaced from said outer tube and open 95 at both ends with one of the latter supported on said outer tube adjacent its open end, a heating coil within said inner tube and electrical connections between said head and coil for heating the latter.

3. In a syringe, a head provided with a recess, a partition across said recess, a tubular casing secured in said recess, a sleeve extending through said partition, an outer tube within and spaced from said casing 105 with an open end supported by the casing, and a closed end supported on said sleeve, said tube having apertures therein adjacent its open end, an inner tube spaced from said outer tube and open at both ends with one of the latter supported on said outer tube adjacent its open end, a heating coil within 110 said inner tube and electrical connections between said head and coil for heating the latter.

4. In a syringe, a head provided with a recess, a partition across said recess, a tubular casing secured in said recess, a sleeve extending through said partition, an outer tube within said casing having a closed end supported on said sleeve, said tube being open at its opposite end and provided with apertures adjacent said open end, an inner tube spaced from said outer tube with open 120 ends one of which is spaced from said outer tube and the other supported on the latter adjacent its open end, a heating coil within 125 said inner tube and electrical connections between said head and coil for lubricating the latter.

5. In a heating element for a hot air syringe, the combination with an outer tube which has one end open and expanded and its other end closed, of a second tube within 5 the former also having an expanded end engaging within the corresponding end of the outer tube, a coil attaching portion resting within the expanded end of the inner tube and held therein by forming the end 10 of the outer tube over it, a heating coil extending between the attaching portion and the closed end of the outer tube, the outer tube having circulating air openings adjacent its expanded end communicating 15 with the space between said tubes.
6. In a syringe, a tubular hand grip provided with a recess, a tubular casing secured in said recess and extending at an angle to said grip, a supporting member extending 20 into the end of said casing in said recess, an apertured outer tube spaced from said casing within the latter having an outer end engaging said casing and an inner end

formed inwardly for engagement with said supporting member, an inner tube spaced 25 from said outer tube and open at both ends, a heating coil in said inner tube, and electrical connections between said hand grip and coil for heating the latter.

7. In a syringe, a hand grip having a 30 recess therein, a tubular casing secured in said recess having an electrically conductive portion, an outer tube spaced from said casing within the latter and having an aperture therein adjacent its outer end, an inner 35 tube spaced from said outer tube and having an opening at its inner end, a heating coil within said inner tube, means for supporting the ends of said coil and connecting its outer end with said conductive portion of the 40 casing, and connections for supplying current to the latter and the inner end of said coil.
